UNITED STATES PATENT OFFICE

160,688

MULTITRAY SERVING RECEPTACLE OR
SIMILAR ARTICLE

Bertram J. Brock, Encino, Calif.

Application January 29, 1949, Serial No. 562

Term of patent 3½ years

(Cl. D44—7)

To all whom it may concern:

Be it known that I, Bertram J. Brock, a citizen of the United States, residing at Encino, in the county of Los Angeles and State of California, have invented a new, original, and ornamental Design for Multi-tray Serving Receptacle or Similar Article, of which the following is a specification, reference being had to the accompanying drawing, forming part thereof.

Figure 1 is a perspective view of a multi-tray serving receptacle, showing my new design;

Figure 2 is a top plan view;

Figure 3 is a vertical, medial sectional view, the plane of section being indicated by the line 3—3 of Figure 1 and the direction of view by the arrows; and

Figure 4 is an exploded perspective view thereof.

I claim:

The ornamental design for a multi-tray serving receptacle or similar article, substantially as shown.

BERTRAM J. BROCK.
